JOHN S. SKELLY, OF MONONGAHELA, PENNSYLVANIA, ASSIGNOR TO COMBUSTION ENGINEERING CORPORATION, OF NEW YORK, N. Y., A CORPORATION OF NEW YORK.

SCREW-FEED STOKER.

1,405,948.

Specification of Letters Patent. Patented Feb. 7, 1922.

Application filed November 19, 1919. Serial No. 329,122.

To all whom it may concern:

Be it known that I, JOHN S. SKELLY, a citizen of the United States, residing at Monongahela, county of Washington, State 5 of Pennsylvania, have invented a certain new and useful Improvement in Screw-Feed Stokers, of which the following is a full, clear, and exact description.

My invention relates to screw feed stokers 10 and has for its object to provide a new and improved screw feed stoker. One feature consists in the use of two feed screws in the same retort, acting together on the same body of coal to move it through the retort. 15 Another feature consists in means for rotating such juxtaposed screws in opposite directions, while another feature consists in the relative position of the threads of the two screws. 20 The invention may be employed in stokers of various kinds, but for convenience is shown embodied in a stoker built somewhat upon the lines of the stoker shown in patent to W. R. Wood, No. 818,010, granted April 25 17, 1906.

The following is a description of an embodiment of my invention, reference being had to the accompanying drawing, in which,

Fig. 1 shows a transverse section of a 30 stoker embodying my invention; Fig. 2 shows a longitudinal section partly on the line 2—2 and partly on the line 2^a—2^a, Fig. 1, with end portions of each screw broken away in order to more clearly 35 show the portions of the other screw;

Fig. 3 shows in end elevation two adjacent stokers and a single means for operating the screw feeds therein; and

Fig. 4 shows a plan view of adjacent portions of juxtaposed screws used in embodying my invention.

Referring more particularly to the drawing, 1, 2 are stationary and movable tubular grate bars of a stoker grate having their 45 upper ends supported by walls 3 of a retort and their lower ends supported by walls 4 of air chambers. The bars 2 are provided with lugs forming notches in which flanges 5 upon oscillating rocker bars 50 6 fit so that when the bars 6 are oscillated the grate bars 2 are reciprocated. 7 is an ordinary dumping ash grate. The rocker bars 6 are supported by walls 8, which with the walls 4 form the secondary air chambers 10 and with the walls 3 form primary

air passages 9 for air supplied to the inner ends of the bars 1 and 2. The bars 1 and 2 are tubular, as shown in dotted lines, having inlet ports at their upper ends connecting with the incoming air chambers 9 and outlet ports at their lower ends discharging into the air chambers 10. 11 is a hopper for holding the supply of fuel which at its lower end discharges into a passage in line with the retort and directly upon the forward ends of the screws. In the retort are two parallel juxtaposed feed screws 12 and 13 mounted on suitably journaled shafts, the screw 12 having a right-hand screw and the screw 13 having a left-hand screw. 70 These screws are so disposed that their faces along a horizontal plane passing through their diameters are always opposite to one another, as shown in Fig. 4, and corresponding points in their faces uniformly approach each other during the travel of the points below the plane of the axes of the screws and uniformly move away from each other during the travel of the points above the plane of the axes of the screws. The screws 75 taper toward their inner ends so that the capacity of the screws uniformly decreases toward their inner ends and the axes of the screws converge toward their inner ends so that the screws are uniformly in close 80 proximity throughout their extent. The screws are also in close proximity with the bottom of the retort and the retort is shaped to conform with the peripheries of the lower portion of the screws as shown in Fig. 1. 90 With this construction it will be apparent that the screws will uniformly co-operate to feed the fuel from the time it leaves the hopper until it passes from the retort, and the screws will act directly and uniformly 95 on all the fuel at the bottom of the retort as well as the rest of the fuel without the assistance of boosters or similar devices. Attached to the sides of the retort are overhanging deflectors 14 and 15, which assist 100 in holding the screws in place and also aid in the distribution of the fuel passing through the retort and upward to the grate bars. The screws 13 of two adjacent stokers (Fig. 3) are driven clockwise by gears 16 105 through screws 17 mounted on a common shaft 18. Connected to the shafts of the screws 13 are geared pinions 19 which mesh with gear pinions 20 mounted upon the shafts of the screws 12 so that when the 110

gears 13 are rotated clockwise the gears 12 are rotated counterclockwise.

The screws 12 and 13 taper toward their inner ends so that the capacity of the screws 5 as they extend to the back end of the retort decreases, with the result that they tend to cause the fuel to rise at all points along the length of the retort.

With this construction, when fuel is 10 placed in the hopper 11 it comes in contact with the ends of the juxtaposed screws adjacent to the mouth thereof and is propelled by their joint action into and along the retort, filling the same so that it flows 15 over upon the upper ends of the grate bars down which it moves slowly on account of the longitudinal movements of the movable bars. The inner sides of the two screws, being the sides which move upward, assist in 20 producing the upward flow of the fuel as well as in producing the longitudinal movement thereof. The curved lower surfaces of the deflectors 14 and 15 assist in holding the screws in place, while their curved upper 25 surfaces assist in directing the flow of fuel upwardly toward the top of the retort and the upper ends of the grate bars. In Fig. 3 I have shown a plurality of stokers operated from a single screw shaft 18 and it is 30 obvious that the number operated from that same shaft can be varied as desired, and that the speed of the feed can be varied by varying the speed of the shaft 18.

As is common in this general type of 35 stoker, air is fed into the tubular passages of the bars through the inlet ports at their upper ends and discharged through the outlet ports at their lower ends into the air chambers 10 beneath the grate from which 40 it passes upward through the grate to the superimposed fuel. The feeding mechanism is simple and efficient and is particularly adapted for supplying fuel to stoker grates of the movable tubular bar type.

45 As will be evident to those skilled in the art, my invention permits of various modifications without departing from the spirit thereof or the scope of the appended claims.

What I claim is:

50 1. In a stoker furnace, a retort having at its bottom two juxtaposed rotating feed screws, a hopper discharging directly upon

the outer ends of said screws, and means for rotating said screws in combination with inclined grate bars extending downwardly 55 from said retort.

2. A stoker furnace having in combination a retort, two co-operating feed screws at the bottom of the retort tapering toward their inner ends, and means for rotating the 60 screws in opposite directions.

3. A stoker furnace having in combination a retort, two co-operating feed screws at the bottom of the retort tapering toward their inner ends and arranged with their 65 axes converging toward their inner ends to position the screws with their peripheries a uniform distance apart throughout their extent, and means for rotating the screws in opposite directions. 70

4. A stoker furnace having in combination a retort, a pair of screws capable of rotating in opposite directions extending longitudinally of the retort and arranged in close proximity to each other and to the 75 bottom of the retort to enable them to co-operate to feed the fuel directly from the bottom of the retort, and means for thus rotating the screws.

5. A stoker furnace having in combination a retort, a pair of feed screws capable of rotating in opposite directions extending longitudinally of the retort and constructed and arranged with their faces along a horizontal plane passing through their diameters opposite to one another so that the movements of corresponding points in their edges uniformly approach each other during the travel of the points below the plane of the axes of the screws and uniformly move 90 away from each other during the travel of the points above the axes of the screws, and means for thus rotating the screws. 85

6. A stoker furnace having in combination a single chamber retort, two feed screws therein extending the length thereof and juxtaposed so as to be closely adjacent to one another, gears connecting the screws so as to cause them to turn in opposite directions, a hopper discharging directly over 100 the outer ends of the screws, and means for rotating said gears. 95

JOHN S. SKELLY.
